(57) **CLAIM**

The ornamental design for a motor car body, as shown and described.

DESCRIPTION

Fig. 1 is a front, top, left perspective view of a motor car body showing my new design therefor, the broken line portions being environment only and forming no part of the design throughout the drawings;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a rear, top, right perspective view thereof.
